DESIGN FOR A COMBINATION DINING PLATE AND SERVICE TRAY

Walter T. Blackinton, Detroit, Mich.

Application September 10, 1936, Serial No. 64,799

Term of patent 7 years

To all whom it may concern:

Be it known that I, Walter T. Blackinton, a citizen of the United States, residing at Detroit, in the county Wayne, and State of Michigan, have invented a new, original, and ornamental Design for a Combination Dining Plate and Service Tray, of which the following is a specification, reference being made to the accompanying drawing, forming a part thereof in which:

Fig. 1 is a perspective view of the articles showing my design.

Fig. 2 is a sectional view taken on line 2—2 of Fig. 1.

Fig. 3 is a sectional view taken on line 3—3 of Fig. 1.

Fig. 4 is a fragmentary sectional view taken on line 4—4 of Fig. 1.

I claim:

The ornamental design for a combination dining plate and service tray as shown.

WALTER T. BLACKINTON.
